ADJUSTABLE LOCK

Erastus C. Deal, Rye, N. Y., assignor to Deal Slide-Lock Devices, Inc., New York, N. Y., a corporation of New York

Application February 19, 1947, Serial No. 729,529

9 Claims. (Cl. 16—193)

1

The present invention relates to adjustable locks and more particularly to an advance or improvement over adjustable locks of the type disclosed in my prior Patent No. 2,380,030.

With certain applications of slide locks it is advisable to provide an adjustable lock that is "biased" in such manner that greater force is required to move it in one direction than to move it in an opposite direction. Constructions of this sort are useful, for example, to support windows in that the lock should be easily movable upwardly when the window is lifted and yet must positively support the weight of the window until some additional downwardly directed force is applied in a direction tending to close the window. Such a biased type of adjustable lock is preferably of variable capacity so that it may be adapted to support different weights of windows or sash or so that it may be selectively set or varied to operate in accordance with particular desired force.

The present invention contemplates the provision of an adjustable lock of compact and relatively simple construction which meets the above and other requirements and which extends the field of usefulness of adjustable locks.

An object of the present invention is to provide a new and improved adjustable lock.

Another object of the invention is to provide an improved adjustable lock which may be moved in different directions under the influence of different pressures.

Another object of the invention is to provide an adjustable lock which may be capacitively set to operate under different desired pressures or forces.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

Fig. 1 is a sectional view showing one form of the present lock in assembled relationship;

Fig. 1a is a fragmentary sectional view showing the parts of Fig. 1 in another position;

Fig. 1b is an exploded perspective view illustrating the parts shown in Fig. 1;

Fig. 1c is a sectional view taken along the line 1c—1c of Fig. 1;

2

Fig. 2 is a perspective view illustrating slightly modified parts which may be used with the lock shown in Fig. 1;

Fig. 2a is a sectional view, partly broken away, showing the parts of the lock of Fig. 2 assembled in a lock;

Fig. 3 is an exploded perspective view illustrating a related form of the invention;

Fig. 3a is a sectional view, partly broken away, showing the form of Fig. 3 in assembled relationship;

Fig. 4 is an exploded perspective view illustrating another related form of the invention;

Fig. 4a is a sectional view, partly broken away, showing the form of Fig. 4 in assembled relationship;

Fig. 5 is an exploded perspective view illustrating another form of the invention;

Fig. 5a is a sectional view, partly broken away, showing the lock of Fig. 5 in assembled relationship;

Fig. 6 is an exploded perspective view showing another related form of the invention; and

Fig. 6a is a partly broken away sectional view showing the form of Fig. 6 in assembled relationship.

Referring more particularly to Figs. 1, 1a, 1b and 1c of the drawings there is shown a frame portion 1 of a window for holding a sheet of glass or other transparent material, adapted to be secured by screws, bolts or the like 2 to a bracket-like member 4. The bracket part 4 may have laterally extending portions 5 and 6 adapted to extend into a channel member or guideway 7 within which are located the operating parts of the present adjustable lock. The laterally extending portions 5 and 6 of the bracket 4 are adapted to receive an intermediately disposed saddle or coupling member 8 provided with laterally extending portions 10 and 11 adapted to be received within and guided by the channel member or guideway 7. The laterally extending portions 10 and 11 of the coupling member 8 are shown provided with ears or lugs 13 for retaining the coupling member in assembled relationship with respect to the guideway 7 and the guideway 7 is preferably provided with oppositely disposed inwardly extending flanges 14 for co-operating with the lateral extensions 10 and 11 of the coupling member to maintain operating parts in assembled relationship.

The bracket or means which serves to carry or support a window or other object may, for purposes of clarity, be referred to as "window-supporting" or "object-supporting" means. But it is not intended to thereby infer that such means

or member must actually be carrying or supporting a load at all times, as that may or may not be true.

The guideway 1 will generally be secured to a window opening by screws or bolts that extend through apertures 16 in the guideway 1, the laterally extending screws or bolts holding the guideway 1 fixed in position at the sides of a window opening.

The invention will be described chiefly with reference to its utilization at only one side of a window but in general usage a similar construction and adjustable lock will be used at each side of the same window. As the adjustable locks and channels at each side of the window are similar a description of one will suffice for both.

The mechanism or parts which serve to facilitate movement of the lock with a window and yet securely retain the window in adjusted position is shown located within the guideway 1 within the confines of the coupling or saddle member 8 and beneath the bracket member 4.

The locking or holding means shown in these Figs. 1, 1a, 1b, and 1c includes wedge-like members 17 and 19 provided with complementary inclined surfaces 17a and 19a between which may extend a strip or length of flexible ribbon or cable 20, the latter being secured to the guideway 1 adjacent its extension by spotwelding, soldering or the like. While any suitable material may be utilized for the flexible ribbon or cable 20, a thin steel ribbon has performed satisfactorily in actual usage. A force or pressure tending to urge the wedge members 17 and 19 toward each other serves to press their outer side edges more firmly into engagement with adjacent wall portions of the guideway 1. The flexible ribbon 20 tends to facilitate desirable spreading of the gripping wedges and to promote smoother operation of the wedges.

A spring or other resilient means 22 located between the lower tab portion 10 of the coupling member 8 and the lower wedge 19 tends to urge the latter wedge toward the upper wedge 17 and a slot or recess 23 in the lower wedge assists in maintaining the spring 22 in position. The upper wedge 17 is normally urged toward the lower wedge 19 by a resilient means or spring 25, the spring 25 resting against the upper surface of the wedge 17 and against the lower end of a nut or collar 28 which extends around a bolt or screw 26 that has a collar or enlarged portion 18 positioned beneath the upper tab or shoulder 10 of the coupling member 8. The bolt 26 extends upwardly through an aperture 29 in the tab 10 so that its upper end may be rotated upon inserting a suitable tool into its slot disposed in the space between the oppositely disposed flanges of the guideway 1. The upper spring 25 is preferably a folded or zig-zag type made of suitable spring steel.

For purposes of convenience the spring or resilient means 22 will be hereinafter referred to as the "locking" spring and the spring or other resilient means 25 as the "load" spring. Since the wedges 17 and 19 disposed intermediate the tab portions 10 and 11 are normally subjected to the force or effect of the locking and load springs 22 and 25, the wedges will normally be forced or pressed toward each other and also outwardly into operative engagement with side wall portions of the guideway 1.

Movement of the lock and wedges in response to manual pressure or force applied to the window frame 1 is transmitted from the frame 75

1 to the wedges 17 and 19 by operating pins or protuberances 31 and 32 carried by the upper and lower wedges shown projecting through slots or openings 34, 35 and 36 in the coupling member 8 and bracket member 4. It will be noted that the operating pin 31 of the upper wedge is shown extending through only the aperture 34 in the coupling member 8 and that the operating pin 32 of the lower wedge extends through elongated openings or slots of both the coupling and bracket members. The bracket opening 36 may be concealed by a cover plate 33 bolted or otherwise attached to the bracket.

When lifting force is applied to the window frame 1 (in a direction tending to open a window) the upper edge of the tab 6 of the bracket 4 presses upwardly against the lower tab 11 of the coupling member 8 and tends to move it upwardly; this applies an upwardly directed force against the underside of the operating pin 31 carried by the upper wedge 17 and tends to move this operating pin and the upper wedge 17 upwardly away from the lower wedge 19. The force applied to the operating pin 31 is thus a "pulling" force and its effect tends to overcome the locking action of the two complementary wedges which engage with the side walls of the guideway 1. As the wedge 17 moves upwardly the tab 11 of the coupling member 8 presses against the locking spring 22 and this locking spring in turn presses against the lower wedge 19 to cause the latter to trail or follow along behind the upwardly moving wedge 17. During such movement portions of the flexible strip 20 pass between adjacent surfaces 17a and 19a of the moving wedges. When the upwardly directed force is released from the window frame 1 the effect of the locking spring 22 and load spring 25 are effective to press the wedges toward each other and to spread them outwardly into engagement with the side walls of the guideway 1. The weight of the window itself also tends to lock the wedges even more securely into engagement with the side walls of the guideway as this weight is applied in what may be termed a "pushing" direction. The upper tab portion 10 of the coupling member 8 presses downwardly on the upper wedge 17 through the bolt 26, threaded member 28, and load spring 25 to firmly lock the wedges into engagement with the walls of the channel or guideway 1.

The locking spring 22 is preferably of relatively low capacity or such that it exerts a minimum resilient effect against the lower wedge 19; the effect is readily overcome upon applying a lift force to the window frame 1 and yet it facilitates trailing movement of the lower wedge 19 behind the upper wedge 17 and immediate locking of the mechanism in desired position.

The load spring 25 is preferably controllable by the bolt 26 and threaded member 28, as will be more fully brought out, so that it is adapted to exert greater effective force than the locking spring 22. From the constructions illustrated in Figs. 1, 1a, 1b and 1c it will be clear that approximately one-half the weight of the window and its sash or frame is carried by the load spring 25, the other half being carried by a similar spring contained within a lock at the opposite side of the same window.

When force is applied to the window frame 1 in a direction tending to close the window the laterally extending tab portion 5 of the bracket 4 presses downwardly upon the bolt 26 and its cooperating threaded member 28, in opposition to

the load spring 25, and moves the bolt 26 and threaded member 28 downwardly until the upper edge 36a of the slot 36 in the bracket 4 comes into contact with the operating pin 32 carried by the lower wedge 19. The force required to so move the bracket 4 and compress the load spring 25 is equivalent to that required to overcome the effect of the load spring 25 over and above that which is utilized for supporting the window and the frame or sash 1. The load spring 25 will 10 usually be partially compressed due to the weight of the window and sash which it is supporting and the window sash will be normally yieldably supported so that in instances where it is subject to vibration it may bounce or yield slightly in 15 opposition to the supporting load spring 25. It is desirable to obtain a setting of the load spring 25 that is sufficient to yieldably support the window and sash at all times and to require the application of a minimum amount of force, in 20 addition to the weight of the window itself, in order to close the window.

With the present invention one lock is adapted to support a variety of different window weights and a most suitable or desirable capacity or loading of the load spring 25 may be obtained by the variable screw or bolt 26 and the threaded member 28 which presses against the load spring 25 in opposition to the resilient effect thereof. When the bolt 26 is rotated sufficiently that the threaded member 28 is in an extended downward position (Fig. 1a) the load spring is compressed a considerable amount and exerts a large opposition to movement of the frame 1 and bracket 4 prior to the edge 36a of the slot 36 coming into 35 contact with an operating pin 32 of the lower wedge 19. Thus a relatively large force must be applied in opposition to the load spring 25 prior to unlocking or releasing the window 1 and the lower wedge 19 for movement to a different position.

When the nut or collar 28 is in a retracted upward position (achieved by rotating the bolt 26 so as to move the threaded member 28 in an upward direction) the load spring 25 is stressed to a minimum amount and the window 1 and bracket 4 may be moved under the influence of less pressure; the edge 36a of the slot 36 may be more easily moved into contact with the operating pin 32 of the lower wedge 19 to release 40 the lock. To facilitate obtaining different settings of the nut or member 28 it is shown provided with a flattened surface 30 that is normally positioned close to the inner surface of the coupling member 8; this construction holds the nut 28 against rotation with the bolt 26 and results in longitudinal movement of these two parts with respect to each other so as to vary the capacity of the load spring 25. The capacity of the load spring 25 may thus be varied to support windows of heavy or light weight; the pressure under which the lock moves may be predetermined. The particular setting of the bolt 26 and threaded member 28, and capacity of the load spring 25, is preferably such as to yieldably support the window and to yet permit downward movement thereof with slight additional effort. While similar load or capacity varying means may be provided at each end of the lock such is not generally necessary since the locking spring 55 may be of fixed capacity due to the fact that it is not normally called upon to do other than maintain a closed relationship of the upper and lower wedges.

A window sash provided with locks of the fore- 75

going described type may be lifted or lowered by grasping the sash at any convenient point. While the load spring 25 is set at comparatively greater effective capacity than the locking spring 22 and yieldably supports the window sash, only a relatively light pressure is required to push the window downwardly for the reason that this additional required force is added to that applied by the weight of the window itself.

Figs. 2 and 2a illustrate a form of the invention along lines of that described. A coupling member 40 is shown with upper tab 42 thereof receiving a rotatable bolt or member 43 carried by non-rotatable nut 45, through intermediation of which the effective capacity of a coil or helical spring 44 may be varied. The upper slotted end of bolt 43 projects through an opening at the upper tab 46 of bracket member 47 and a tab at lower end of this bracket similar to tab 6 of Fig. 1 serves to support a tab on coupling member 40 similarly to the foregoing description of Figs. 1 and 1b. Collar 41 co-operates with a bolt shoulder to hold the bolt in the position shown in Fig. 2a.

The operating of the lock of Figs. 2 and 2a is similar to that above described with respect to Figs. 1, 1a, 1b and 1c. Utilization of a helical spring may be desirable in some instances and Figs. 2 and 2a show one such form of the invention.

The structure illustrated in Figs. 3 and 3a may be desired, in some instances, from a constructional standpoint. In this form of the invention a coupling member 48 has a tab 49 at one end thereof adapted to fit into and at the bottom of a spring-positioning recess in the lower wedge member with the locking spring 51 resting against the outer side of the tab 49. The coupling member 48 is provided with elongated openings 52 and 53 through which project operating pins 54 and 55 carried by the bracket member 50 that are adapted to move the upper and lower wedges during actuation of the mechanism. The lower edge of the bracket 50 shown in this figure is provided with a tab portion 58 adapted to be received and guided by the guideway 60 and has at the upper end thereof an apertured tab 61 adapted to fit around a threaded settable bolt or pin 62. The bolt 62 also has its upper end projecting through an apertured tab 64 of the coupling member 48 and this tab 64 may fit within and be guided by oppositely disposed inwardly projecting flanges of the guideway or channel 60. A shoulder 63 on the bolt 62 serves to retain it in operative relationship.

Rotation of the bolt 62 is effective to vary the compression or effectiveness of a load spring 66 shown positioned intermediate the tab 61 of the bracket 50 and a threaded plate or nut 67 carried within the guideway 60. As the bolt 62 is rotated in one direction the nut 67 moves downwardly within the guideway 60 to decrease the effective force of the spring 66; as the bolt 62 is turned in an opposite direction the nut 67 is caused to move toward the tab 61 to increase the effective force caused by the spring 66. The nut 67 may have a flat side which prevents rotation of it with the bolt 62. The effective force of the spring 66 may thus be varied to obtain a desired effective force or capacity that tends to resist objectionable movement of a window in downward direction. The window is yieldably supported by the spring 66. The effective capacity of the spring may be varied to support the weights of different windows; where a heavy window is

to be supported, the bolt 62 may be turned so as to cause the spring 66 to exert a comparatively large force and where a relatively light weight window is to be supported, the bolt 62 may be rotated to obtain a correspondingly small capacity or effective force of the spring 66.

In operation, when the window is raised the upper side of the operating pin 54 moves into contact with the upper part of the aperture 65 shown in the upper wedge 59 and pulls the wedge along the guide channel 60, with the lower wedge 56 moving along behind the upper wedge. When the window is moved toward closed position, the tab or flange 61 at the upper part of the bracket 50 moves downwardly, in opposition to the spring 66, and the lower operating pin 55 carried by the bracket 50 comes into contact with the bottom of the aperture 63 in the lower wedge 56 and continued movement pulls or presses the lower wedge downwardly, tending to move it away from the upper wedge. The wedges may thus be released from locking engagement with the side walls of the channel 60 and the window may be moved downwardly or upwardly, as desired.

Figs. 4 and 4a illustrate another form of the invention generally similar to that described in connection with the previously described forms but which has a capacity-determining bolt threaded into the supporting bracket and a load spring effective against an exterior side of a coupling member tab.

As a window frame carrying the bracket 70 is lifted an operating pin 71 carried by the bracket 70 moves into contact with the upper edge of the aperture 69 in the upper wedge and pulls it along the guideway 72, the lower wedge following behind due to the action of the locking spring 64 and cover member 75. When the window and its bracket 70 are moved downwardly toward closed position the operating pin 76 moves into contact with the lower edge of a recess 77 in the lower wedge member and pulls it along the guideway 72, with the upper wedge member in following relationship due to the cover or saddle member 75 which rests against the end of the upper wedge.

The upper and lower wedges and locking spring 64 may be inserted within the coupling member 75 and the whole inserted as a unit in a guideway 72. Thereafter the load spring 78, spacer 79, setting bolt 80 and bracket 70 may be assembled with the channel and with the parts previously inserted in the guideway.

In Figs. 5 and 5a there is illustrated a form of the invention which does not embody a coupling member. In this form of the invention the window attachment bracket 82 is shown provided with lower and upper tabs 83 and 84 provided by forming and bending portions of the bracket 82 inwardly in such manner that the tabs are adapted to fit into a guideway 86 and to receive the oppositely disposed inwardly projecting flanges of the guideway in slots 87 disposed at opposite sides of the tabs 83 and 84. A locking spring 88, locking wedges 89 and 91, load spring 92 and spacer member 94 are disposed within the guideway intermediate the bracket tabs 83 and 84.

The locking spring or other resilient means 88 located between the lower tab portion 84 and the lower wedge 89 tends to urge this latter wedge toward the upper wedge 91 and a recess may assist in maintaining the spring 88 in position. The upper wedge 91 is normally urged toward

the lower wedge by the resilient means or spring 92, the spring 92 rested against the upper surface of the wedge 91 and against the end of the spacer member or slug 94. The spacer member 94 and upper wedge are shown provided with centering or retaining pins 93 and 99 to assist in holding the spring 92 in operative position. The spacer member 94 is held downwardly in opposition to the force of the spring 92 by a screw or bolt 101 threaded into the upper tab portion 83 of the bracket 82.

Projecting operating lugs or pins 95 and 96 carried by the bracket 82 are adapted to fit into recesses or apertures 97 and 98 of the upper and lower wedges respectively in such manner that raising a window attached to the bracket 82 causes the upper edge of the operating pin 96 to come into contact with the upper edge of the wedge recess 98 to "pull" the upper wedge along the guide channel 86. Movement of a window and the bracket 82 downwardly causes the operating pin 95 to come into contact with the lower edge of the recess 97 so that the lower wedge will be pulled along through the guideway 86. The trailing wedge follows along behind the "pulled" wedge with portions of the flexible strip 100 passing between the wedge faces.

The spacer member 94 is shown as a block with straight sides set into the guideway 86, the capacity of the load spring 92 being varied by turning the bolt 101 to move the spacer member 94 with respect to the wedge 91 and thus vary capacity or effect of load spring 92.

In the form shown in Figs. 6 and 6a a load carrying spring 105 is located adjacent the lower part of the adjustable lock. In some instances this construction may be deemed desirable as contributing toward a neater appearing lock and since in some cases it may facilitate assembly of the lock with a window frame.

The window frame 106 has secured thereto a supporting bracket 107 which has a lateral extension 109 supported on the load spring 105 so that the window is carried by the spring 105 and the latter may absorb objectionable vibration caused by road shocks and the like. A support bar or member 110 has a handle or arm 112 by which the window may be raised or lowered. When the handle 112 is moved upwardly from the position illustrated an operating pin or projection 113 comes into contact with the upper edge of an aperture 115 in the upper wedge member 116 and serves to pull the upper wedge member slightly away from the lower edge 117 so that the lock and window may be moved to a different position. If it is desired to lower the window a user presses downwardly upon the handles 112 and thus causes an operating pin 118 to come into contact with the bottom part of the aperture 119 in the lower wedge member 117; in order for this to obtain it is necessary that the support bar 110 move downwardly to sufficiently compress the load spring 105.

Adjustment of the load spring 105 may be performed by rotating the bolt or screw 119 so that it moves inwardly or outwardly through the threaded aperture 121 in the support bar 110. When the bolt is moved inwardly it compresses the load spring 105 and increases its effectiveness in the lock through the intermediation of a spacer element 122 and when moved outwardly it allows the load spring 105 to expand and thus reduce the effective capacity of the spring and its force exerted in the lock.

With the construction disclosed in Figs. 6 and

6a the compression-determining screw 119 is somewhat less exposed to view and in addition to contributing to a more attractive appearance it may also reduce the possibility of persons tampering with the lock.

It will be seen that the present invention provides a new and improved adjustable lock which is particularly adaptable to supporting windows. The locks of the present invention may be located at any desired location on a window, preferably at opposite sides thereof; they allow ready lifting of the sash and yet securely retain it at any desired open or closed position. The locks may be set or selectively varied so that they support windows of different weights and so that they may operate in accordance with a particular amount of applied force. While the locks of the present invention securely hold a window at any desired location, only a relatively light additional pressure is required to move a window toward a further closed position. The present locks are of relatively simple construction and require relatively few operating parts.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. In a device of the class described, the combination of a guideway, wedge-like members in said guideway, a bracket member carried by said device for supporting an article, means for retaining said wedge-like and bracket members in assembled relationship, a pair of spiral compression springs in said guideway operatively connected with the wedge-like members and normally exerting different resilient effects against wedge-like members whereby there is required greater force to move the bracket in one direction with respect to the guideway than in an opposite direction, and movable means operatively connected with one of said springs for varying the compression and resulting resilient effect exerted by at least one of said spiral compression springs to thereby vary the force required to move the device in one direction with respect to the guideway.

2. In a device of the class described, the combination of a guideway, locking wedges in and movable along said guideway, resilient means normally urging said wedges toward each other and into locking engagement with the guideway, an object-supporting member, means retaining said locking wedges and object-supporting member in assembled relationship, second resilient means operatively disposed between one of said locking wedges and said object-supporting member adapted to support said object-supporting member and normally exerting a greater effective force than said first-mentioned resilient means, and adjustable means for selectively determining the effective force exerted by one of said resilient means.

3. In a device of the class described, the combination of a guideway, locking wedges in and movable along said guideway, a bracket-like member, means operatively connecting the bracket-like member with the locking wedges for movably supporting the bracket-like member, portions operatively connected with said bracket-like member and projecting into the guideway, resilient means intermediate one of said projecting por-

tions and a locking wedge adapted to normally urge said wedges toward each other and into engagement with the guideway, second resilient means intermediate another of said projecting portions and a locking wedge normally yieldably supporting said bracket-like member and normally exerting a greater effective force against said locking wedges than said first-mentioned resilient means, and adjustable means for selectively determining the effective force exerted against said locking wedges by said second resilient means.

4. In a device of the class described, the combination of a guideway, holding wedges in and adjustable along said guideway, a window-supporting member, means operatively connecting the window-supporting member with the holding wedges for movably supporting the window-supporting member, portions operatively connected with said window supporting member projecting into said guideway, resilient means intermediate one of said projecting portions and a holding wedge normally urging said wedges toward each other and into engagement with the guideway, second resilient means intermediate another of said projecting portions and another of said wedges, and adjustable means effective upon said latter-mentioned projecting portion and second resilient means for varying the effective pressure exerted by said second resilient means.

5. In a device of the class described, the combination of a guideway, holding wedges in and movable along said guideway, a window-supporting member, laterally extending means operatively connecting the holding wedges and window-supporting member, portions operatively connected with said window supporting member projecting into said guideway adjacent outer ends of said holding wedges, resilient means intermediate one of said projecting portions and a holding wedge adapted to normally press said wedges in engagement with the guideway, second resilient means normally exerting greater force than said first resilient means intermediate another of said projecting portions and a holding wedge adapted to normally urge said latter projecting portion and latter holding wedge apart from each other, and means carried by and movable with respect to said latter-mentioned projecting portion of the window-supporting member for varying the effective force exerted by said second resilient means.

6. In a device of the class described, the combination of a guideway, holding wedges in and movable along said guideway, a window-supporting member, lateral means operatively connecting said holding wedges and said window-supporting member, portions operatively connected with said window supporting member projecting into said guideway at locations spaced from said holding wedges, resilient means intermediate one of said projecting portions and a holding wedge adapted to normally maintain said wedges in engagement with the guideway, second resilient means intermediate another of said projecting portions and a wedge and normally exerting greater force than said first resilient means, a movable spacer member resting against said second resilient means, and means in said guideway carried by and movable with respect to said latter-mentioned projecting portion of the window-supporting member for varying the effective force exerted by said second resilient means.

7. In a device of the class described, the combination of a guideway having oppositely spaced walls, a plurality of overlapping wedge members

11

in and engageable with and slidable along said opposite walls of the guideway, means for retaining a member in assembled relation with said guideway and in association with said wedge members whereby said member may be supported by the wedge members upon engagement thereof with the guideway, resilient means including a portion operatively interposed between the wedge members and said member adapted to yieldably support the latter member and including a portion urging the wedge members into engagement with the guideway, said first-mentioned portion of the resilient means normally opposing movement of the said member in one direction along the guideway, means movable with said member for selectively contacting portions of the wedge members to disengage them from the guideway and facilitate movement of said member and said wedge members along the guideway, and selectively settable means effective against a portion of said resilient means for varying the resilient effect exerted thereby.

8. In a device of the class described, the combination of a guideway having oppositely spaced walls, a plurality of overlapping wedge members in and engageable with and slidable along said opposite walls of the guideway, means for retaining a member in assembled relation with said guideway and in association with said wedge members whereby said member may be supported by the wedge members upon enlargement thereof with the guideway, resilient means including a portion operatively interposed between the wedge members and said member adapted to yieldably support the latter member and including a portion urging the wedge members into engagement with the guideway, said first-mentioned portion of the resilient means normally opposing movement of the said member in one direction along the guideway, means movable with said member for selectively contacting portions of the wedge members to disengage them from the guideway and facilitate movement of said member and said wedge members along the

12

guideway, and selectively settable screw means effective against a portion of said resilient means for varying the amount of deformation thereof and the resilient effect exerted thereby.

9. In a device of the class described, the combination of a guideway having oppositely spaced walls, a plurality of overlapping wedge members in and engageable with and slidable along said opposite walls of the guideway, means for retaining a member in assembled relation with said guideway and in association with said wedge members whereby said member may be supported by the wedge members upon engagement thereof with the guideway, resilient means including a portion operatively interposed between the wedge members and said member adapted to yieldably support the latter member and including a portion urging the wedge members into engagement with the guideway, said first-mentioned portion of the resilient means normally opposing movement of the said member in one direction along the guideway, means movable with said member for selectively contacting portions of the wedge members to disengage them from the guideway and facilitate movement of said member and said wedge members along the guideway, and selectively settable means in said guideway effective against a portion of said resilient means for varying the resilient effect exerted thereby.
